ATTACHMENT FOR SAW BLADES

Harry E. Grahn, Bronx, N. Y.

Application March 7, 1946, Serial No. 652,505

1 Claim. (Cl. 33—75)

1

This invention relates to saws of various kinds and classes, comprising a saw-blade and handle portion. More particularly, the invention deals with saws having means adjustably mounted on the saw-blade adjacent the handle portion to form of the saw and in combination with the back edge of the saw-blade, means for marking a workpiece at different angles with respect to one edge of the workpiece, for example, in forming of the saw a square or miter. The novel features of the invention will be best understood from the following description when taken together with the accompanying drawing, in which certain embodiments of the invention are disclosed, and in which the separate parts are designated by suitable reference characters in each of the views, and in which:

Fig. 1 is a plan view of a saw showing my attachment in a normal position with respect to the handle, with part of the construction broken away.

Fig. 2 is an enlarged section on the line 2—2 of Fig. 1.

Fig. 3 is a view similar to Fig. 2 showing the attachment in an offset or flexed position preparatory to shifting the same to different positions on the saw-blade; and

Fig. 4 is an enlarged section on the line 4—4 of Fig. 2, showing only the saw-blade and the attachment thereon.

In Fig. 1 of the drawing, I have shown at 10 a blade of a conventional type of saw, the blade having a straight back edge 11 and an angular saw tooth edge 12. At 13 is shown a handle portion secured to the wide end portion of the saw by screws or other fastening devices 14.

The handle member adjacent the straight back edge 11 is recessed, as seen at 15, to receive enlarged pivot portions 16 of two back members or bars 17 and 18, note Figs. 2 and 3. Passed through the blade 10 and fixedly secured in the enlarged portions 16 of the bars 17 and 18 is a pivot pin 19 securely held in the bars by key-pins, at at 20—21. The bars 17 and 18 have straight faces or longitudinal edges 22 and 23, note Fig. 4, which operate in conjunction with the straight back edge 11 of the saw in forming different angular positions with respect to said edge. For example, at right angles to the edge 11, as indicated at 22' in Fig. 1, and at forty-five degrees to the edge 11, as indicated at 22'', it being understood that the edge 23 of the bar or backing 18 assumes the same positions.

The bar 17 around the pivot pin 19 has a recess 24 in which is placed a heavy spring 25, so as

5 to firmly maintain the pivot ends of the bar 18 upon the saw-blade 10. The recess 24 is formed on the inner surface 26 of the bar 17, and another and deeper recess 27 opens through this surface and in which is arranged a lighter coil spring 28 which is adapted to bear upon the surface of the blade 10.

In the construction shown, the blade 10 has 10 three apertures 29, 30 and 31, all equally spaced radially with respect to the pivot 19, but positioned on the blade to fixedly support the backing attachment comprising the bars 17 and 18, first adjacent the handle 13, as shown in full lines in Fig. 1, and then in the two positions 15 where the surface 22 is at right angles and forty-five degrees to the edge 11, as indicated at 22'—22''. This positioning of the attachment or the bars 17 and 18 is accomplished by a pin 20 32 having a pressed or drive fit in the bar 18 and protruding inwardly beyond the inner surface 33 of said bar to enter the apertures 29, 30 and 31.

The inner protruding end of the pin has slightly 25 rounded corners as at 34, note Fig. 4, to freely 30 guide the pin into the respective apertures 29, 30 and 31, whereas the pin is fitted snugly in the apertures and particularly the apertures 30 and 31 to maintain a rigid backing in providing a T-square and the miter, as shown in the two 35 dotted line positions of Fig. 1 of the drawing.

The surfaces 26 and 33 are relieved at the free 40 ends of the bars, as seen at 26' and 33' in order to prevent these surfaces from contacting the blade 10 as the bars assume the different positions shown in Figs. 2 and 3. The ends of the bars are also bevelled, as seen at 35, note Fig. 1, to conform to the general contour of the handle 13 and eliminate any protruding corner which might be objectionable.

The upper surface of the handle 13, as seen 45 in Fig. 1 of the drawing or the surface adjacent the bar 17, has a thumb-notch or recess 36 to facilitate engagement of the finger with the rear or back surface 37 of the bar 17 in the operation of moving the attachment from the normal full line position shown in Fig. 1, which may be regarded as a collapsed position, to either of the 50 dotted line positions shown in said figure. In this operation, the bar 17 is first depressed to disengage the pin 32 from the aperture 29, after which the bar is swung outwardly. Thereafter, the downward pressure may be removed from the bar 17 and the pin 32 will then ride along the surface of the blade until the first aperture 30 is reached. When the pin registers with this

aperture, it will automatically snap into the aperture, returning the bar 17 to the position shown in Fig. 2, in which position the bars 17 and 18 are rigidly locked and become a unit part of the blade.

Considering Fig. 2, it will be apparent that in the normal locked position of the attachment the surface 33 bears snugly upon the face of the saw-blade 10, whereas the surface 26 extends outwardly in an angular or inclined position, in the direction of the free end of said bar. However, in this position, it will appear that the entire attachment is disposed within the boundaries of the upper and lower surfaces of the handle 13 and this is true in any position of the attachment and is particularly desirable when the attachment is in the collapsed or normal position so as to not provide any obstructions on the saw when the saw is in use.

Now noting Fig. 3, it will appear that when pressure is applied on the bar 17, the surface 33 is moved away from the blade adjacent the key-pin 32 and the surface 26 contacts the blade 10 adjacent the apertures 29, 30 and 31. This position clears the inner end of the pin 32 to allow the attachment to be freely swung on the blade. In this connection it will be noted that there has been little or no movement of the pivot end portions of the bars 17 and 18, the spring 25 serves to hold these bars in snug and taut arrangement. In fact, in actual practice, the holding at the pivot end is such as to slightly spring or flex the saw-blade and it is this flexure in combination with the springs 25 and 28 that results in the snapping of the key-pin 32 into the respective apertures.

It will be apparent that by employing additional apertures, such as the apertures 29, 30 and 31, other angular positions may be obtained in scribing different angles upon a workpiece preparatory to cutting the same. It will appear from a consideration of Fig. 1, that a slight clearance is provided between the square and mortise attachment and the handle when the attachment is in the normal or full line position. This is to insure positive movement of the key or lock pin into the aperture 29.

By providing the attachment, the saw may be converted into a T-square, wherein the attachment provides the equivalent of the backing of the square for placement against the edge of a board or other sheet to be marked. The straight edge 11 provides a long marking edge, considerably longer than the average T-square used by the carpenter or workman. By disposing the rods 17 and 18 on each surface of the saw-blade 10, the edge 11 may be extended to the right or to the left for marking purposes. In this way, forty-five degree lines with respect to the edge may be scribed or marked in either one of two directions. The foregoing will also be true in connection with other angular positions which can be employed by increasing the number of holes 29-31 employed in the blade 10. The structure shown is the simple basic requirements for conventional uses, but some workmen may desire to mark other angles.

By incorporating the attachment comprising the two bars 17 and 18 on the saw, the need for a workman to carry the extra tool, namely a square, in his tool kit is obviated. Furthermore, material saving of time will be effected by reason of the fact that the square or mortise marking tool is directly available on the saw and markings can be quickly and easily made without having to take the time to find or pick-up a square or miter and thereafter to find or pick-up the saw to be used.

It will also be understood that each saw of a complete kit may have the attachment applied thereto, particularly in that the attachment is of simple and economical construction and will not add materially to the cost of the saw. Furthermore, the addition of the attachment to the saw adds a little weight to the handle end of the saw which provides a better balance in the use thereof and by reason of its weight, adds to the driving power of the saw.

Having fully described my invention, what I claim as new and desire to secure by Letters Patent is:

25 A square and miter attachment for saw blades having straight back edges, said attachment comprising a pair of bars, means comprising a pin coupled with said bars for pivotally and yieldably mounting one end of the bars with a saw blade, one bar, at a predetermined distance from said pivot coupling having a key element secured thereto and projecting from the inner surface thereof, the saw blade having a recess adapted to be snugly engaged by said key element in retaining the bar in predetermined position on said blade, the other bar having, on the inner surface thereof, a recess spaced from, but adjacent, said key element, a spring in said recess and adapted to seat on the saw blade to tensionally hold the key element in operative position, and the inner adjacent surfaces of the bars at the free end portions thereof being relieved beyond said key element to provide pivotal and yielding movement of the bars against the action of said spring in coupling and uncoupling the key element with the blade.

HARRY E. GRAHN.
